UNITED STATES PATENT OFFICE

2,042,455

VOLUMETRIC LIQUID DISPENSER

William E. Barrott, Aurora, Ind.

Application May 7, 1935, Serial No. 20,251

4 Claims. (Cl. 221—98)

This invention relates to dispensing containers and has for an object to provide a novel container that will store the liquid and dispense an exact predetermined quantity of the liquid with minimum effort, without measuring, and without waste.

A further object is to provide a container adapted to dispense mixed drinks, spirituous liquors, drugs and chemicals where accuracy is required.

A further object is to provide a liquid dispenser which will be formed of a few simple inexpensive and durable parts, and which will be neat and compact in appearance.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a cross sectional view of a liquid dispenser constructed in accordance with my invention.

Figure 2 is a front elevation of the dispenser.

Referring now to the drawing in which like characters of reference designate similar parts in the various views, 10 designates a cylindrical vessel having gudgeons 11 on the end walls which are received in bearing boxes 12 carried by inverted V shaped brackets 13 which may be bolted as shown at 14 or otherwise secured to a table top 15, counter, or other support. The brackets 13 constitute supports upon which the vessel may be easily turned axially in either direction.

The vessel 10 is preferably formed of transparent material so that the liquid level in the vessel 40 may be observed. A partition 16 is secured to the cylindrical wall of the vessel and extends substantially parallel with a diameter of the vessel. The partition coacts with the subtended arcuate wall in forming a measuring chamber. An inlet 17 is formed in the partition 16 above the liquid level in the vessel when the vessel is full and this inlet forms means through which the measuring compartment is filled when the vessel is rotated clockwise to submerge the inlet below the liquid 50 level in the vessel. The partition may be formed of any desired material and in practice one end of the partition may be provided with a flange 18 which is riveted as shown at 19 or otherwise sealed liquid tight to the wall of the vessel. The inlet 55 17 may be formed simply by terminating the par-

tition 16 short of the wall of the vessel and providing a flange 20 over which the liquid overflows back into the vessel when the measuring compartment is too full. However the inlet may be formed simply by a slot or opening of any desired configuration formed in the partition.

The measuring compartment is provided preferably with spaced outlets 21 located at different levels on the wall of the vessel for selectively dispensing a predetermined measured quantity of liquid from above these levels in the compartment. Each outlet is preferably closed by a flap valve 22 having hinge ears 23 through which a pintle 24 carried by the outlet is passed to hinge the valve at the top to the outlet. A grip 25 projects forwardly from the outer face of the valve and forms means for opening the valve. An arcuate leaf spring 26 is secured at one end as shown at 27 to the outlet and bears with its free end against the outer face of the flap valve to hold the valve closed against the pressure of the liquid in the measuring chamber.

A pair of perforated baffle plates 28 is disposed within the vessel, these plates preferably having base flanges 29 which are secured by rivets 30 or other suitable connectors to the cylindrical wall of the vessel. The plates extend radially from the wall of the vessel and constitute agitators to thoroughly mix the contents of the vessel when the vessel is rotated to either limit of movement.

A yielding stop 31 is disposed on the outer face of the cylindrical wall of the vessel and preferably comprises a yoke 32 the bight of which is riveted as shown at 33 to the cylindrical wall of the vessel. A pin 34 is slidably mounted in openings in the branches of the yoke and is provided at one end with a head 35 between which and the adjacent branch of the yoke a helical spring 36 is confined under tension. A nut 37 is screwed on to the opposite end of the pin and bears against the outer face of the adjacent branch of the yoke. Tightening of the nut will increase the tension of the spring 36.

A stationary abutment 38 is arranged exteriorly of the vessel in the path of the yielding stop 35. The abutment may be simply a U shaped bar which embraces the vessel longitudinally, the legs of the bar being provided with flanges 39 which may be rigidly secured in any preferred manner to the supporting brackets 13. When the yielding stop 31 impinges against the abutment 38 the shock will be cushioned by the pin 35 yielding against the tension of its spring 36 and at the same time the vessel will be vibrated by yielding of the pin 34 and assist in ridding the

measuring compartment of entrapped air when in the filling position.

A stop 40 is disposed on the cylindrical wall of the vessel and is spaced from the yielding stop 5 to engage the abutment 38 and limit rotation of the vessel in a counter-clockwise direction. The stop 40 may be simply an angle iron riveted to the wall of the vessel as shown at 41.

The vessel is provided with a flanged filling opening 42 which is closed by a cap 43 having an axial plug 44 which is tapered to snugly engage a similar taper formed on the flange of the filling opening. The cap is threaded on to the flange of the filling opening as shown at 45. The plug 44 is provided with an axial opening 46 through which air may enter the vessel to permit the contents to flow out evenly and smoothly. The air inlet opening is closed by a ball check valve 47 which is confined against a tapered seat 48 formed in the mouth of the opening, by a helical spring 49 which is confined under tension between the valve and an annular shoulder 50 formed at the inner end of the air inlet opening.

An arm 51 projects upwardly from the abutment 38 and is provided with an offset finger 52 underneath which the ball 47 rides when the vessel is turned counter-clockwise to dispensing position. The finger is provided with a cam surface 53 which depresses the valve 47 against the tension of its controlling spring 49 and holds the air inlet 46 unsealed so that the contents of the measuring chamber will flow evenly and freely from the outlet 21. When the vessel is turned in a clockwise direction the ball check valve is carried away from the finger 53 and is immediately seated by the spring 49 to seal the air inlet 46 and prevent leakage of the contents of the vessel when the vessel is turned clockwise to fill the measuring compartment.

In operation the vessel is turned clockwise until the measuring compartment is submerged below the surface of the liquid in the vessel as shown by dotted lines in Figure 1. The measuring compartment is quickly filled with a predetermined volume of liquid through the inlet 17. The vessel may now be turned in a counter-clockwise direction to elevate the inlet 17 above the surface of the liquid in the vessel. Any one of the outlets 21 may be opened to dispense a predetermined quantity of liquid above the particular level controlled by the selected outlet as will be understood.

From the above description it is thought that the construction and operation of my invention will be fully understood without further explanation.

What is claimed is:

60 1. A liquid dispenser comprising a support, a cylindrical vessel revolvably mounted on the support, a partition extending from the cylindrical wall of the vessel substantially parallel with a diameter of the vessel and coacting with the subtended arcuate wall in forming a measuring compartment, an inlet in the partition disposed above the liquid level in the vessel when the vessel is full and through which the measuring compartment is filled when the vessel is revolved to submerge the inlet below the liquid level in the vessel, spaced outlets in the wall of the compartment disposed at different levels in the compartment for selectively dispensing a predetermined

measured quantity of liquid from the compartment, spaced stops on the wall of the vessel, a stationary abutment exposed exteriorly of the vessel in the path of the stops for limiting rotary movement of the vessel in either direction, and an air vent in the wall of the vessel. 5

2. A liquid dispenser comprising a support, a cylindrical vessel revolvably mounted on the support, a partition extending from the cylindrical wall of the vessel substantially parallel with a diameter of the vessel and coacting with the subtended arcuate wall in forming a measuring compartment, an inlet in the partition disposed above the liquid level in the vessel when the vessel is full and through which the measuring compartment is filled when the vessel is revolved to submerge the inlet below the liquid level in the vessel, an outlet in the wall of the compartment through which the contents of the compartment may be dispensed, a spring pressed pin slidably mounted on the wall of the vessel, a stationary abutment disposed exteriorly of the vessel in the path of the pin for limiting rotary movement of the vessel in one direction, said pin engaging the abutment and vibrating the vessel when the vessel is turned to fill the compartment, and an air vent in the wall of the vessel. 10

3. A liquid dispenser comprising a support, a cylindrical vessel revolvably mounted on the support, a partition extending from the cylindrical wall of the vessel substantially parallel with a diameter of the vessel and coacting with the subtended arcuate wall in forming a measuring compartment, an inlet in the partition disposed above the liquid level in the vessel when the vessel is full and through which the measuring compartment is filled when the vessel is revolved to submerge the inlet below the liquid level in the vessel, an outlet in the wall of the compartment through which the contents of the compartment may be dispensed, a yoke on the wall of the vessel, a spring pressed pin slidably mounted in the yoke, a stationary abutment disposed exteriorly of the vessel in the path of the pin for limiting rotary movement of the vessel in one direction, said pin engaging the abutment and vibrating the vessel when the vessel is turned to fill the compartment, and an air vent in the wall of the vessel. 15

4. A liquid dispenser comprising a support, a vessel revolvably mounted on the support, an air vent in the wall of the vessel, a spring pressed check valve in the air vent, an arm carried by the support adapted to engage the valve and hold the valve open when the vessel is turned to one limit of movement, a partition extending from the cylindrical wall of the vessel substantially parallel with a diameter of the vessel and coacting with the subtended arcuate wall in forming a measuring compartment, an inlet in the partition disposed above the liquid level in the vessel when the vessel is full and through which the measuring compartment is filled when the vessel is revolved to submerge the inlet below the liquid level in the vessel, an outlet in the wall of the compartment through which the contents of the compartment may be dispensed, spaced stops on the wall of the vessel, and a stationary abutment carried by said support and disposed in the path of the stops for limiting rotary movement of the vessel in either direction. 20
